UNITED STATES PATENT OFFICE.

GOVERNOR D. WARREN, OF CRIPPLE CREEK, COLORADO.

ROCK-DRILL.

No. 887,363.

Specification of Letters Patent.

Patented May 12, 1908.

Application filed July 16, 1902, Serial No. 115,829. Renewed October 9, 1907. Serial No. 396,657.

To all whom it may concern:

Be it known that I, GOVERNOR D. WARREN, a citizen of the United States, residing at Cripple Creek, in the county of Teller and State of Colorado, have invented new and useful Improvements in Rock-Drills, of which the following is a specification.

My invention relates to improvements in rock drills, and pertains particularly to that class in which steam or compressed air is used as the motive power.

The object of my invention is to provide a rock drill in which the piston is partially rotated during the backward movement thereof, so that the drill will strike in a different position on each forward movement of the piston in order that a round opening will be drilled.

Another object of my invention is to provide a drill adapted to accomplish the above results, in which the piston is subject to as little strain as possible in causing the rotation thereof.

A still further object of my invention is to provide a drill in which there is both a central and end pressure which greatly increases the power of the drill in comparison with the size of the cylinder.

In the accompanying drawings, Figure 1 is a longitudinal sectional view of my improved rock drill. Fig. 2, is a transverse sectional view taken on line $x-x$ of Fig. 1. Fig. 3, is a rear end view. Fig. 4, is a detached enlarged view of the ratchet disk. Fig. 5, is an end view of the pawl carrying member. Fig. 6, is a horizontal sectional view of a modification partly broken away.

Referring now to the drawings, A represents a cylinder which is elongated in form and provided with an enlarged central bore A', the purpose of which will be hereinafter more fully described. Communicating with the upper portion of said enlarged central bore, is an oblong opening B adapted to receive the valve carrying block C, which is provided with the transverse circular opening a having at one end an opening b by means of which it is connected with the steam or compressed air supply pipe and leading from opposite sides of said opening are the steam supply ports c and c' leading outwardly and communicating with the steam conveying ports d and d' carried by the upper portion of the cylinder, and said ports lead to opposite ends of the cylinder.

Extending transverse the valve carrying

block above and parallel with and communicating with the valve opening a, is the exhaust opening D which is in communication with the outside atmosphere on the opposite side from the steam supply pipe, and may have connected thereto a pipe D' adapted to convey the exhaust to any desired place. Within said opening a is a valve E which is provided with a central steam supply opening e which extends clear through the valve, and communicating with the said opening are the transverse openings e¹ and e² which are adapted to register one at a time with the ports c and c' carried by the valve carrying block. The said valve carrying block is provided with an opening F in its lower face, and the valve E opposite said opening is provided with a downwardly extending operating arm F' which is adapted to be reciprocated by the reciprocation of the piston. The upper portion of the said valve between the ports e¹ and e² is provided with a circular depression G which is adapted to communicate with the exhaust opening D and one of the supply ports d' when the steam is being admitted to the opposite end of the cylinder through the opening c.

The forward end of the cylinder A is provided with the packing head 1 which is made in two sections 2 and 3 and held together by the bolts 4, and said packing head is provided with the packing 5. Passing through said head is the piston rod H which forms an air tight joint and the forward end of the piston rod carries the drill chuck which may be of any form as this forms no part of my present invention. The inner end of the piston rod H carries a piston I which is of an elongated form, and is provided with a reduced central portion I', the purpose of which will be hereinafter more fully described. The said piston is made in two sections, i and i' and the section i carried by the inner end of the piston rod H is provided with a screw-threaded opening J which is adapted to receive the screw-threaded end j of the reduced portion. Each of the said portions i and i' of the piston is provided with an annular groove or recess k and k' adapted to receive the packing K and K' and thus making an air-tight joint on each side of the reduced central portion. Surrounding said reduced portion of the piston, are two longitudinally movable rings L and L' which are in the path of the downwardly extending arm F' of the valve E and adapted to move the said arm

back and forth during the reciprocation of the piston, which operates the valve and thus first admits steam in one end of the cylinder and then the other.

5 Surrounding the central reduced portion of the piston between the two rings L and L' is a coiled spring l², the tendency of which is to force the rings apart.

10 I provide the end of the valve E opposite the inlet opening with an opening k² which allows the steam or air to fill the entire enlarged central bore of the cylinder and thus I provide the drill with a central pressure which greatly increases the power of the drill, 15 which I will now proceed to describe.

15 The steam, as before stated, completely fills the enlarged central bore of the cylinder between the rings L and L' and when the piston is in the position shown in Fig. 1, 20 the drill is near or at the end of the backward stroke. The ring L fits snugly around the reduced portion of the piston, and is provided with a packing l adjacent thereto and thus an air-tight connection is formed therewith. The steam entirely fills the enlarged bore between the rings and is therefore on 25 both sides of the rings L and L', and thus during their movement forward and backward the pressure is equalized.

30 The forward ring L' is provided adjacent the reduced portion of the piston with transverse air or steam openings l', and the steam pressure gained in said central portion is equal to that of the area of the shoulder 35 formed by the reduced central portion of the piston. The ring L' is carried forward until it engages the wall formed by the enlarged central bore and is there seated and as the piston continues to travel forward, the steam 40 is admitted through the opening l' and engages the shoulder of the piston and aids in carrying it forward, and the backward pressure against said ring would be less than the forward pressure, as the area thereof against 45 which the steam is bearing is less at its forward edge than at its rear edge and thus the washer is held seated. The washer would also aid in carrying the piston forward as shown in Fig. 1, as the forward area of the 50 washer exposed to the steam pressure is less than that of the rear side, thus the tendency of the steam is to force the ring forward and at the same time the piston. The steam pressure is at the same time keeping the rear 55 washer L against the shoulder of the cylinder, and thus there is no resistance against the opposite end of the piston, until near the end of the stroke, when the pressure at the end of the piston and the momentum it has 60 gained unseats the ring L and carries it forward, thus operating the valve and changing the direction of the piston. By this construction, it will be clearly seen that the 65 central pressure is only utilized on the forward stroke of the piston or in other words,

on the drilling stroke of the drill. The washers L and L' are so positioned on the piston that when they are moved forward or backward they do not pass the steam inlet opening, but are directly opposite the same 70 and thus steam is not admitted directly behind either ring.

In the modification shown in Fig. 6, the cylinder is made the same bore throughout its length, and the piston is not provided with 75 the rings 6 and 7, and the downwardly extending valve operating arm is operated directly by the shoulder formed by the reduced central portion of the piston in a manner similar to that of Fig. 1. 80

The rear end of the cylinder is provided with an enlarged opening 9, said opening extending up adjacent the end of the supply opening d', and within said opening is a circular flat disk 10 which forms the rear end of 85 the cylinder against which the backward pressure of the steam is resisted. Beyond the said disk is a ratchet disk 11, which is of less diameter than the disk 10 and is provided with a forwardly extending member 12 extending through the opening 13 in the disk 10, and provided with spirally arranged 90 grooves 14. The said member 12 passes within an opening 15 in the outer end of the piston and said opening 15 is provided with 95 inwardly projecting spirally arranged projections adapted to enter the spiral grooves on the outer end of the member 12. As before stated, the said ratchet disk is of a size less than the enlarged bore of the outer end, 100 and surrounding said disk is a metal packing 16 which is adapted to engage the outer periphery and frictionally prevent the same from being turned too far during the forward stroke of the piston. The said metal packing 105 16 is provided with a peripheral groove 16' which is in communication with an opening 16² in the cylinder, and whereby the said groove is filled with lubricating oil. The said peripheral groove has communication with 110 the inner ends of a number of openings 16³ which are adapted to feed oil to the ratchet disk. The said disk has its rear side provided with nine coarse ratchets 11', the purpose of which I will now proceed to describe. 115 Within said enlarged bore of the cylinder beyond the ratchet disk 11, is an elongated cylindrical member 17, and said member is provided with four openings 18, which have their inner end reduced, and within said openings are four horizontal pawls 19 adapted to engage the ratchets carried by the disk 11. The said pawls have their inner ends reduced, and surrounding said reduced portions are coil springs 20 which bear against the wall 120 formed by the reduced portion of the pawl whereby they are normally outwardly spring pressed and held in contact with the ratchet disk 11. The pawl carrying member is provided with a central recess 21 and the ratchet 125 disk 11 is provided with a central recess 22. The said pawls are provided with a central recess 23 and the ratchet disk 11 is provided with a central recess 24. The said pawls are provided with a central recess 25 and the ratchet disk 11 is provided with a central recess 26. The said pawls are provided with a central recess 27 and the ratchet disk 11 is provided with a central recess 28. The said pawls are provided with a central recess 29 and the ratchet disk 11 is provided with a central recess 30. The said pawls are provided with a central recess 31 and the ratchet disk 11 is provided with a central recess 32. The said pawls are provided with a central recess 33 and the ratchet disk 11 is provided with a central recess 34. The said pawls are provided with a central recess 35 and the ratchet disk 11 is provided with a central recess 36. The said pawls are provided with a central recess 37 and the ratchet disk 11 is provided with a central recess 38. The said pawls are provided with a central recess 39 and the ratchet disk 11 is provided with a central recess 40. The said pawls are provided with a central recess 41 and the ratchet disk 11 is provided with a central recess 42. The said pawls are provided with a central recess 43 and the ratchet disk 11 is provided with a central recess 44. The said pawls are provided with a central recess 45 and the ratchet disk 11 is provided with a central recess 46. The said pawls are provided with a central recess 47 and the ratchet disk 11 is provided with a central recess 48. The said pawls are provided with a central recess 49 and the ratchet disk 11 is provided with a central recess 50. The said pawls are provided with a central recess 51 and the ratchet disk 11 is provided with a central recess 52. The said pawls are provided with a central recess 53 and the ratchet disk 11 is provided with a central recess 54. The said pawls are provided with a central recess 55 and the ratchet disk 11 is provided with a central recess 56. The said pawls are provided with a central recess 57 and the ratchet disk 11 is provided with a central recess 58. The said pawls are provided with a central recess 59 and the ratchet disk 11 is provided with a central recess 60. The said pawls are provided with a central recess 61 and the ratchet disk 11 is provided with a central recess 62. The said pawls are provided with a central recess 63 and the ratchet disk 11 is provided with a central recess 64. The said pawls are provided with a central recess 65 and the ratchet disk 11 is provided with a central recess 66. The said pawls are provided with a central recess 67 and the ratchet disk 11 is provided with a central recess 68. The said pawls are provided with a central recess 69 and the ratchet disk 11 is provided with a central recess 70. The said pawls are provided with a central recess 71 and the ratchet disk 11 is provided with a central recess 72. The said pawls are provided with a central recess 73 and the ratchet disk 11 is provided with a central recess 74. The said pawls are provided with a central recess 75 and the ratchet disk 11 is provided with a central recess 76. The said pawls are provided with a central recess 77 and the ratchet disk 11 is provided with a central recess 78. The said pawls are provided with a central recess 79 and the ratchet disk 11 is provided with a central recess 80. The said pawls are provided with a central recess 81 and the ratchet disk 11 is provided with a central recess 82. The said pawls are provided with a central recess 83 and the ratchet disk 11 is provided with a central recess 84. The said pawls are provided with a central recess 85 and the ratchet disk 11 is provided with a central recess 86. The said pawls are provided with a central recess 87 and the ratchet disk 11 is provided with a central recess 88. The said pawls are provided with a central recess 89 and the ratchet disk 11 is provided with a central recess 90. The said pawls are provided with a central recess 91 and the ratchet disk 11 is provided with a central recess 92. The said pawls are provided with a central recess 93 and the ratchet disk 11 is provided with a central recess 94. The said pawls are provided with a central recess 95 and the ratchet disk 11 is provided with a central recess 96. The said pawls are provided with a central recess 97 and the ratchet disk 11 is provided with a central recess 98. The said pawls are provided with a central recess 99 and the ratchet disk 11 is provided with a central recess 100. The said pawls are provided with a central recess 101 and the ratchet disk 11 is provided with a central recess 102. The said pawls are provided with a central recess 103 and the ratchet disk 11 is provided with a central recess 104. The said pawls are provided with a central recess 105 and the ratchet disk 11 is provided with a central recess 106. The said pawls are provided with a central recess 107 and the ratchet disk 11 is provided with a central recess 108. The said pawls are provided with a central recess 109 and the ratchet disk 11 is provided with a central recess 110. The said pawls are provided with a central recess 111 and the ratchet disk 11 is provided with a central recess 112. The said pawls are provided with a central recess 113 and the ratchet disk 11 is provided with a central recess 114. The said pawls are provided with a central recess 115 and the ratchet disk 11 is provided with a central recess 116. The said pawls are provided with a central recess 117 and the ratchet disk 11 is provided with a central recess 118. The said pawls are provided with a central recess 119 and the ratchet disk 11 is provided with a central recess 120. The said pawls are provided with a central recess 121 and the ratchet disk 11 is provided with a central recess 122. The said pawls are provided with a central recess 123 and the ratchet disk 11 is provided with a central recess 124. The said pawls are provided with a central recess 125 and the ratchet disk 11 is provided with a central recess 126. The said pawls are provided with a central recess 127 and the ratchet disk 11 is provided with a central recess 128. The said pawls are provided with a central recess 129 and the ratchet disk 11 is provided with a central recess 130.

member is also provided with a central opening 22, registering with the opening in the pawl member, and a pin has its opposite ends resting within the openings in the ratchet 5 disk and the pawl carrying member, whereby the ratchet disk is prevented from twisting or being ground by the ratchet. The inner end of the pawl block rests against the ring or packing 16, and bearing against the opposite 10 end is a cylindrical block 25 which fits within the annular enlarged recess in the rear end of the cylinder, and the outer periphery carries a packing ring 26 to form an air-tight connection. Bearing against the rear end of 15 said block and resting within a recess carried thereby, is a rubber block 27, and extending horizontally across said block is a leaf spring 28 which is drawn inwardly by the bolts 29 and thus firmly clamp the pawl block 17 between 20 the circular disk 10 and the block 25, thus holding the same against rotation. It is readily seen that this means of holding the pawl block provides a cushioned head which will give and allow the pawl block and the 25 ratchet disk to be forced rearwardly should there be any undue backward pressure thereon, thus obviating the breaking of the ratchet teeth carried by the disk.

The lower edge of the cylinder adjacent the 30 rear end is provided with a downwardly extending member 30 which has secured therein an elongated horizontal sleeve 30' which is provided with a screw-threaded opening 31 through which passes the feed screw 32 which 35 is of the ordinary form used in rock drills of this character. The forward end of said horizontal sleeve 30' is provided with an annular recess 33, which is adapted to receive the sleeve 34, which is adapted to cover the screw 40 32 and to protect it from exposure to the atmosphere, and dust and dirt. The lower end of the forward head of the piston is also provided with a downwardly extending member 35, which is provided with a recess 36, adapted 45 to receive the outer end of the sleeve 34 whereby it is securely supported.

Having thus described my invention, what I claim, and desire to secure by Letters Patent, is:—

50 1. A rock drill comprising a cylinder having an enlarged central opening, a drill operating piston within the cylinder and having a reduced central portion, means for admitting pressure at each end of the piston and within 55 the reduced central portion of the piston, and means carried by the reduced portion of the piston for exerting pressure on the piston on its forward stroke.

2. A rock drill comprising a cylinder having 60 an enlarged central opening, a drill operating piston within said cylinder and having a reduced central portion, two rings loosely mounted upon said reduced portion of the piston, and means for admitting steam between 65 said rings, whereby one bears against

the piston and the opposite one against the cylinder, substantially as described.

3. A rock drill comprising a cylinder having an enlarged central opening, a drill operating piston within said cylinder and having 70 a reduced central portion, two rings loosely mounted in said reduced portion of the piston, a spring normally forcing the rings apart, and means for admitting steam between said rings, substantially as described. 75

4. A rock drill comprising a cylinder having an enlarged central opening, a valve above said opening, a valve arm extending within said cylinder, a drill operating piston within the cylinder and having a reduced 80 central portion and a ring carried by said reduced portion of the piston on each side of the valve arm, substantially as described.

5. A rock drill comprising a cylinder having an enlarged central opening, a valve 85 above said opening, a valve arm extending within the cylinder, a drill operating piston within the cylinder and having a reduced central portion, a ring carried by the reduced portion of the piston on each side of the 90 valve arm and a coil spring between said rings, substantially as described.

6. A rock drill, comprising a cylinder having an enlarged central opening, a valve above said opening, a valve arm extending 95 within the cylinder, a drill operating piston within the cylinder and having a reduced central portion, a ring carried by the reduced portion of the piston on each side of the valve arm, and means carried by the valve for admitting pressure between the rings. 100

7. A rock drill, comprising a cylinder having an enlarged central opening, a valve above said opening, a valve arm extending within the cylinder, a drill operating piston within the cylinder and having a reduced 105 central portion, a ring carried by the reduced portion of the piston on each side of the valve arm, a coil spring between said rings, and means operated by the valve for admitting pressure between the rings. 110

8. A rock drill comprising a cylinder having an enlarged central opening, a drill operating piston within said cylinder and having a reduced central portion, and means for utilizing the steam in said central and end openings simultaneously on its forward stroke. 115

9. A rock drill comprising a cylinder, a drill operating piston therein, and means for applying a central and end pressure simultaneously on the forward stroke. 120

10. A rock drill comprising a cylinder having an enlarged central opening, a valve above said opening, a valve arm extending 125 within the cylinder, a drill-operating piston within the cylinder and having a reduced central portion, a ring carried by the reduced portion of the piston on each side of the valve arm, and a coil-spring between said rings. 130

11. A rock-drill comprising a cylinder having an enlarged central opening, a valve above said opening, a valve arm extending within the cylinder, a drill operating piston within the cylinder and having a reduced central portion, a ring carried by the reduced portion of the piston on each side of the valve arm, and means between said rings for holding the same apart. 5
12. A rock drill comprising a cylinder having an enlarged central opening, a valve above said opening, a valve arm extending within the cylinder, a drill operating piston within the cylinder and having a reduced central portion, a ring carried by the reduced portion of the piston on each side of the valve arm, and said valve arm having a passageway, whereby the fluid pressure is admitted between the rings. 10
13. A rock drill comprising a cylinder having an enlarged central opening, a valve above said opening, a valve arm extending within the cylinder, a drill-operating piston within the cylinder and having a reduced central portion, a ring carried by the reduced portion of the piston on each side of the valve arm, a coil-spring between said rings, and said valve arm having a passageway whereby fluid pressure is admitted between the rings. 15
14. A rock drill comprising a cylinder having an enlarged central opening, a valve above said opening, a valve arm extending within the cylinder, a drill-operating piston within the cylinder and having a reduced central portion, a ring loosely mounted upon the reduced portion of the piston on each side of the valve arm, means for admitting fluid pressure between the rings. 20
15. A rock drill comprising a cylinder having an enlarged central opening, a drill-operating piston within the cylinder and having a reduced central portion, and means for utilizing the fluid pressure in said central and end openings simultaneously on the forward stroke. 40
16. A rock drill comprising a cylinder having an enlarged central opening, a drill-operating piston within the said cylinder and having a reduced central portion, a ring mounted on said reduced portion, and means whereby a central and end fluid pressure is simultaneously obtained on the forward stroke of said piston. 50
17. A rock drill, comprising a cylinder, a drill operating piston within said cylinder and having a reduced central portion, means for admitting steam at each end of the piston and within the central reduced portion of the piston, and means carried by the reduced portion of the piston for exerting steam pressure on the piston on its forward stroke. 55
18. A rock drill, comprising a cylinder having an enlarged central opening, a valve above said opening, a valve arm extending within said enlarged opening, a piston within 60

the cylinder and having a reduced central portion, rings carried by said reduced portion on the piston of each side of said valve arm. 75

19. A rock drill, comprising a cylinder, having an enlarged central opening, a valve arm extending within said opening, a piston within said cylinder and having a reduced central portion, rings carried by said reduced portion of the piston, and a spring normally holding said rings apart. 75

20. A rock drill, comprising a cylinder having an enlarged central opening, a valve arm extending within said opening, a piston within the cylinder and having a reduced central portion, rings loosely mounted upon said reduced portion of the piston on each side of said valve arm, and extending within the enlarged opening in the cylinder, a coil spring between said rings and one of said rings having steam passages therethrough and adapted to be closed by the shoulder formed by the reduced portion of the cylinder. 80

21. A rock drill, comprising a cylinder having an enlarged central opening, a valve above said opening, a drill operating piston within the cylinder and having a reduced central portion, means operated by the valve for admitting pressure into the end and enlarged central portion of the said cylinder, and means carried by the reduced portion of the piston for exerting pressure on the piston on its forward stroke. 85

22. A rock drill, comprising a cylinder having an enlarged central opening therein, a piston within the cylinder and having a reduced central portion, a valve above the enlarged portion of the cylinder, and adapted to allow pressure to enter at the end and central portion of the piston, a valve arm carried by the valve and adapted to enter said enlarged and reduced portion of the cylinder and piston, a ring carried by the reduced portion of the piston on each side of the valve arm entering the enlarged opening in the cylinder, a coil spring between said rings, one of said rings having steam passages through the same and adapted to be closed by the shoulder formed by the reducing of the piston. 100

23. A rock drill comprising a cylinder, a valve above said piston, a valve arm carried by the valve and extending into the cylinder adjacent the piston and rings loosely mounted upon the piston on each side of the valve arm. 115

24. A rock drill comprising a cylinder, a piston within the cylinder and having a reduced central portion, a valve above the piston, a valve arm carried by the valve and extending within the reduced portion of the piston and rings loosely mounted upon said reduced portion of the piston on each side of the valve arm. 120

25. A rock drill, comprising a cylinder having an enlarged central opening, a valve above said opening, a valve arm extending 125

within said enlarged opening, a piston within the cylinder and having a reduced central portion, and rings loosely mounted upon said reduced portion of the piston on each side of 5 said valve arm.

26. A rock drill comprising a cylinder having an enlarged central opening, a valve above said opening, a valve arm extending within said enlarged opening within the cylinder and said valve arm having a steam passage way therethrough, and rings loosely mounted upon the reduced portion of the piston on each side of said valve arm.

10 15 27. A rock drill, comprising a cylinder having an enlarged central opening, a valve above said opening, a valve arm extending

within said enlarged opening, a piston within the cylinder, said valve arm having a steam passage-way therethrough, rings loosely mounted upon the reduced portion of the piston on each side of said valve, the forward ring having a steam passage-way adapted to allow the steam to pass therethrough on the rearward stroke of the piston. 20

In testimony whereof I have hereunto set 25 my hand in the presence of two subscribing witnesses.

GOVERNOR D. WARREN.
